[57] ABSTRACT

A laundry machine includes end frames rotatably supporting an outer casing and an inner cylinder. A coupling assembly interlocks the casing with the frame during laundry operations while the cylinder rotates, and interlocks the casing and the cylinder for simultaneous rotation, with the casing and cylinder doors aligned, for bottom unloading and top loading operations. A positioning assembly locates the cylinder, or the interlocked cylinder and casing, in a precise angular position relative to the frame so that the coupling assembly may operate. Electrical and pneumatic controls carry out laundry, unloading and loading, positioning, and coupling operations in a safe and reliable sequence.

LAUNDRY MACHINE

The present invention relates to laundry machines and more particularly to improvements in positioning and coupling structures and controls for rotary commercial washing machines.

Commercial laundry machines including an inner cylinder and an outer casing mounted between end frames are known. One approach to the unloading of such machines has been to pivot the casing and cylinders away from the end frames to a position wherein the casing doors, normally located near the top of the casing, are directed downwardly. In order to avoid the necessity of lifting or pivoting the bulky and massive casing and cylinder, it has been proposed to rotate the casing about its fixed central axis between loading and unloading positions. An example of a laundry machine of this type may be found in my U.S. Pat. No. 3,613,406 issued on Oct. 19, 1971.

During laundry operations of this type of machine, the casing is fixed to the frame while the cylinder and the laundry load contained therein are rotated. During loading and unloading operations, the casing is freed from the frame and fixed to the cylinder with the casing and cylinder doors aligned. When the casing is coupled to the frame, precise positioning of the cylinder is necessary before the uncoupling operation is carried out. Similarly, when the casing is coupled to the cylinder, the cylinder and casing must be precisely positioned relative to the frame before coupling. The secure coupling and precise positioning of the relatively bulky and massive components of a laundry machine present serious difficulties.

A movable casing door and various releasable connections for steam, washing fluids and electrical power may be mounted on the frame for engagement with the casing during laundry operations, and such devices must be retracted prior to rotation of the casing. In use of the laundry machine, these devices as well as the coupling and positioning assemblies, and the drive motors and brakes, must be controlled in predetermined sequences. Many problems arise in the safe and automatic control of the laundry, unloading, loading, positioning and coupling operations.

Among the important objects of the present invention are to provide an improved laundry machine of the type including concentrically rotatable casing and cylinder structures; to provide an improved coupling arrangement for coupling the casing alternatively to the frame and to the cylinder; to provide an improved positioning arrangement for precisely locating the cylinder, or the coupled cylinder and casing, in an exact angular position relative to the frame; and to provide improvements in the safe and automatic control of laundry machines.

Briefly, a laundry machine in accordance with the present invention may include a pair of end frames supporting an inner cylinder and an outer casing for rotation around a common central axis. A coupling assembly is provided to interlock the casing alternatively to the frame or to the cylinder. In accordance with a feature of the invention, a first coupling means serves to interlock the casing with the frame or to free the casing from the frame, while a second coupling means serves to interlock the cylinder with the casing or to free the cylinder from the casing. An actuator moves the second coupling means between positions, and the second

coupling means engages the first coupling means and moves the first coupling means between positions. The movement of the first and second coupling means is such that the casing is never free simultaneously from both the cylinder and the frame.

In accordance with another aspect of the invention, there is provided a positioning assembly for locating the cylinder, or the coupled cylinder and casing, in a predetermined angular position relative to the frame 10 wherein the coupling assembly may be operated. An approximate positioning arrangement first locates the cylinder in a desired region. A precise positioning assembly, operable only when the cylinder has been approximately positioned, then engages the cylinder and moves it to the desired exact position.

Other features of the invention reside in improved control arrangements for safely and automatically controlling the positioning and coupling assemblies as well as other mechanisms associated with the machine such as the casing door, releasable connections to the casing, and the drive motors and brakes.

The invention together with the above and other objects and advantages appear more fully with reference to the following detailed description of the embodiment of the invention illustrated in the drawings, wherein:

FIG. 1 is a front elevational view of a laundry machine constructed in accordance with the principles of the present invention;

FIG. 2 is a side elevational view of the machine of FIG. 1 taken from the left hand side as viewed in FIG. 1;

FIG. 3 is a side elevational view of the machine of FIG. 1 taken from the right hand side as viewed in FIG. 1;

FIG. 4 is a diagrammatic and simplified vertical sectional view of the machine of FIG. 1 illustrating the position of certain components during a washing operation;

FIG. 5 is a view similar to FIG. 4 illustrating the position of components following or prior to a washing operation;

FIG. 6 is a view similar to FIG. 4 illustrating another position;

FIG. 7 is a view similar to FIG. 4 illustrating an unloading position;

FIG. 8 is an enlarged fragmentary sectional view taken along the line 8-8 of FIG. 1 and illustrating the 50 positioning and coupling structures of the machine of FIG. 1;

FIG. 9 is an enlarged sectional view of the structure illustrated in FIG. 8 taken along the line 9-9 of FIG. 8;

FIG. 10 is an enlarged simplified sectional view taken along the line 10-10 of FIG. 2 and illustrating a portion of the positioning structure of the machine of FIG. 1;

FIG. 11 is a side elevational and sectional view of the structure illustrated in FIG. 10;

FIG. 12 is an enlarged sectional view taken along the line 12-12 of FIG. 8;

FIG. 13 is a side view, partly in section, taken from the line 13-13 of FIG. 12;

FIG. 14 is an enlarged fragmentary view of a portion of the structure of FIG. 9 taken from the line 14-14 of FIG. 9;

FIG. 15 is a schematic and diagrammatic illustration of the pneumatic control circuit of the machine of FIG. 1; and

FIG. 16 is a schematic and diagrammatic illustration of the electrical control circuit of the machine of FIG. 1.

GENERAL ARRANGEMENT

In the drawings there is illustrated a laundry machine designated as a whole by the reference numeral 20 and constructed in accordance with the principles of the present invention. Although the illustrated machine 20 comprises a rotary washer suitable for commercial, industrial and institutional installations, features of the present invention may be applied to many types of laundry machines such as washer-extractors and others.

With reference initially to FIGS. 1-7, the washer 20 in general includes a frame structure designated as a whole by the numeral 22 including left and right end frames 24 and 26. Mounted for rotation between the end frames 24 and 26 is a generally cylindrical outer casing 28 including a cylindrical wall 30 and end walls 32 and 34 forming a fluid tight washing enclosure. The casing includes a door opening 36 adapted to be closed during washing operations by a door 38 under the control of a door operating structure generally designated as 40.

Also supported for rotation between the end frames 24 and 26 is an inner cylinder 42 similar in shape to and received within the casing 28. Cylinder 42 functions during washing operations to enclose and support a laundry load and includes a cylindrical perforated side wall 44 permitting fluids contained within the casing 28 to flow into and through the enclosed laundry load. Depending upon the length of the washer 20, the cylinder 42 may be divided into separate compartments by one or more interior walls 46 (FIG. 1) and access to the interior of each compartment of the cylinder 42 is provided by one or more slidably mounted cylinder doors 48 (FIGS. 4-7).

In FIGS. 4-7 the positions of the casing 28 and casing door 36 and of the cylinder 42 and cylinder door 48 are illustrated in somewhat diagrammatic form at several points during washing and unloading-loading operations. In FIG. 4, the washing position is illustrated and it can be seen that the casing door 38 is closed and the cylinder door 48 is also closed. During the laundry operation, the casing 28 is interlocked with the frame 22 and is held against rotation. Washing fluids are introduced within the casing 28, and the cylinder 42 is rotated so that a laundry load held within the cylinder is washed by the fluids.

After the washing operation is completed, the cylinder is positioned as illustrated in FIG. 4 wherein the door of the cylinder 42 is aligned with the door 38 of the casing 28. At this time the cylinder 42 is coupled to the casing 28, and simultaneously the casing 28 is uncoupled from the frame 22. As shown in FIG. 5, the casing door 38 is moved by the door operating structure 40 to a position clear of the door opening 36. At this time the coupled casing 28 and cylinder 42 are rotated to a convenient position as illustrated in FIG. 6 wherein the operator of the washer 20 moves the cylinder door 48 to the open position.

In order to unload the laundry load from the machine 20, the coupled cylinder 42 and casing 28 are then ro-

tated to a downwardly directed position as illustrated in FIG. 7. The laundry load is discharged downwardly into a suitable load handling apparatus such as one or more laundry carts, a conveyor, or the like.

Once the washed load has been discharged from the washer 20, the machine is ready to receive another laundry load. The coupled casing 28 and cylinder 42 are rotated from the position of FIG. 7 through one hundred eighty degrees of rotation to the position illustrated in FIGS. 4 and 5 wherein the door openings of the casing and cylinder are directed upwardly. A laundry load to be washed is then deposited within the cylinder 42, for example by means of a suitable overhead laundry transporting mechanism such as a sling conveyor, a belt conveyor or the like. Thereafter, the cylinder 42 and casing 28 may once again be rotated to the position of FIG. 6 for closing of the cylinder door 48. Prior to beginning a washing cycle, the coupled cylinder and casing are again rotated to the upwardly directed position (FIG. 4) and the casing door 38 is moved to its closed position by means of the door operating structure 40. The cylinder 42 is uncoupled from the casing 28 so that it is able to rotate within the casing 28, and simultaneously the casing 28 is coupled to or interlocked to the frame 22 so that it remains stationary throughout the washing operation.

It will be appreciated that the structural components of the washer 20 such as the casing 28 and cylinder 42 are large in size and heavy. Moreover, a laundry load supported within the cylinder 42 may be quite heavy, particularly when wetted with washing fluids. Nevertheless in carrying out the washing and unloading-loading operations briefly described above, it is necessary accurately, quickly and conveniently to rotate and position the cylinder 42 and casing 28 in various positions. Moreover, it is necessary firmly to interconnect the casing 28 alternatively with the cylinder 42 and with the frame 22. In accordance with an important feature of the present invention, there is provided a novel positioning assembly generally designated by the reference numeral 50 and described below for positioning the cylinder 42, as well as the casing 28 when the casing 28 is coupled to the cylinder 42, accurately, positively and conveniently with respect to the frame 22. In accordance with another important feature of the present invention, there is provided a coupling assembly generally designated by the reference numeral 52 and described in detail below for interlocking the casing 28 alternatively with the frame 22 and with the cylinder 42. In accordance with further features of the present invention, a pneumatic control circuit generally designated by the reference numeral 54 and an electrical control circuit generally designated by the reference numeral 56 control the operation of the washer 20 together with the positioning and coupling assemblies 50 and 52 in an automatic, reliable and safe manner in order to perform washing, unloading and loading functions.

DETAILED DESCRIPTION OF STRUCTURAL COMPONENTS

Proceeding now to a more detailed description of the structural components of the washer 20, as indicated above the frame 22 includes left and right frame members 24 and 26. Each end frame member provides a hollow enclosure for various components of the washer 20 and includes an edge wall 58 and inner and outer

side walls 60 and 62. In many installations of the washer 20, it is desirable to position the washer spaced above a floor surface to permit positioning of laundry conveying devices such as carts or conveyors beneath the casing 28. Thus, there are provided left hand and right hand base members 64 and 66 supporting the end frames 24 and 26 in an elevated position. A platform 68, a stairway 70 and guard rail 72 are provided to permit the operator convenient access to the washer 20.

In order to rotate the cylinder 42, as well as the casing 28 when the casing 28 is coupled to the cylinder 42, there are provided a pair of drive motors 74 supported on the outer wall 62 of the frame members 24 and 26. Disposed within the end frames 24 and 26 at either end of the washer 20 are cylinder drive gears fixed to cylinder trunnions which extend axially outwardly from the ends of the cylinders and into the end frames. Portions of the left hand cylinder drive gear are illustrated in FIGS. 8-11, and this drive gear is designated by the reference numeral 78. Each motor 74 is drivingly coupled to the corresponding cylinder drive gear by means of a drive assembly 80 disposed on the corresponding end frame.

The casing door 38 and door operating structure 40 are supported upon the frame 22 adjacent the topmost portions of the left and right end frame members 24. More specifically, the inner walls 60 of the end frames 24 and 26 support a pair of slide members 84 carrying a carriage 86 mounted for sliding movement in a forward and rearward direction. The door 38 is mounted below the carriage for reciprocal movement in a vertical direction, and a pneumatic cylinder 88 is coupled between the carriage and the door for moving the cylinder either down into engagement with the door opening 36 or up to a position wherein the door is spaced above the casing 28. If desired, plural cylinders 88 may be used. A second pneumatic cylinder 90 is coupled between the frame 22 and the carriage 86 by means of a suitable drive linkage in order to control the movement of the carriage from a forward position (FIGS. 1 and 4) wherein the door is aligned over the door opening 36 and a rearward position (FIGS. 2, 3, 6 and 7) wherein the door is spaced well to the rear of the casing 28. A further description of the structure and operation of the door 38 and door operating structure 40 beyond that required for a complete understanding of the present invention may be found in my copending application Ser. No. 169,376, filed on Aug. 5, 1971, and now U.S. Pat. No. 3,751,947.

In connection with the operation of the electrical control circuit 56 described below, it is desirable to provide electrical indications of the positions of the door 38. As illustrated diagrammatically in FIGS. 4-7, there is provided a switch 91 operated when the door 38 is in its lowermost position closing the door opening 36. A second switch 92 is operated when the door supporting carriage 86 is in its forward position. Another switch 93 is operated in response to movement of the door 38 to its rearward position.

During washing operations when the casing 28 is interlocked with the frame 22, washing fluids are introduced to the interior of the casing 28. Such washing fluids customarily include a mixture of hot and cold water together with other materials, such as soap, bluing, bleach, sour, starch and the like. Also, non-aqueous washing fluids might be utilized in laundry operations of other types. In the illustrated washer 20, the washing

fluids are provided through hot and cold water inlets 94 and 95 and a supply header 96 including a series of pneumatically operated valves 98 for selectively admitting various additive materials. The hot and cold water and additive materials are mixed together in an inlet fitting 100 supported on the right end frame 26.

A fluid supply conduit 102 supported by the casing door 38 extends from the region of the inlet fitting 100 to a central portion of the door 38 for channelling 10 washing fluids into the casing 28 from inlet fitting 100. In order selectively to interconnect the inlet fitting 100 and the fluid supply conduit 102, there is provided a releasable connection 104 operated by a pneumatic actuator 106 (FIG. 15). When the casing 28 is interlocked 15 with the frame 22 and it is desired to introduce washing fluids into the casing 28, the actuator 106 is pressurized and a connection is established for the admission of fluids to the fluid supply conduit 102. When it is desired to free the casing for rotation relative to the frame, the 20 actuator 106 is depressurized and the releasable connection is severed. A further description of the structure and operation of the washing fluid supply system of the washer 20 including the releasable connection 104, beyond that necessary for an understanding of the 25 present invention, may be found in my copending application Ser. No. 169,376, filed on Aug. 5, 1971, and now U.S. Pat. No. 3,751,947.

In order to remove washing fluids from the interior 30 of casing 28, there are provided a pair of dump valve assemblies 108 disposed on the cylindrical casing wall 30 generally diametrically opposite the door opening 36. Each valve assembly 108 may be of the type described in detail in my copending application Ser. No. 169,376, filed on Aug. 5, 1971, and now U.S. Pat. No. 3,751,947. The dump valve assemblies normally serve 35 to seal the casing 28 against the discharge of fluids, and include a pneumatically operated actuator serving selectively to open the dump valve assemblies so that fluid is discharged through the dump valve assemblies 40 into laterally extending discharge conduits 110 supported on the casing 28. Conduits 110 in the operating position of the casing 28 are aligned with and discharge 45 into vertically extending discharge conduits 112 supported on the left and right hand base members 64 and 66 and leading to a suitable fluid receiving device such as a floor drain or the like.

As illustrated in diagrammatic fashion in FIG. 15, the washer 20 is provided with releasable connections in 50 addition to the washing fluid supply connection 104 for the purpose of establishing connections with the casing 28 during washing operations when the casing 28 is interlocked with the frame 22. Thus, there is provided a fluid level releasable connection 114 serving to interconnect conduit 116 supported on frame 22 with a conduit 118 supported on the casing 28. The conduit 116 extends to the interior of casing 28 and conduit 116 extends to a level indicator device in order to provide an indication and/or carry out control functions in response to the level of fluid within the casing 28. Associated with the releasable connection 114 is a pneumatic actuator 120 for interconnecting the conduit 116 and the conduit 118 by closing the connection 114 in response to pressurization of the actuator 120.

In carrying out washing operations it may be desirable to introduce steam into the interior of casing 28 for the purpose of increasing the temperature of washing fluids. For this reason there is provided a steam re-

leasable connection 122 for interconnecting a steam supply line 124 and a steam conduit 126 carried by and leading into the casing 28. A pneumatic actuator 128 is associated with the connections 122 for interconnecting the line 124 and the conduit 126 in response to pressurization of the actuator 128.

In order releasably to establish electrical connections between the frame portion 22 of the washer 20 and the casing 28, there is provided an electrical releasable connection 130 associated with a pneumatic actuator 132. In response to pressurization of the actuator 132, the connection 130 is closed in order to close a group of electrical contacts associated with the connection 130. A switch 133 provides an indication of the condition of the releasable connection 130, and is operated when the connection is fully open.

Reference may be had to my copending application Ser. No. 166,720, filed on July 28, 1971, and now U.S. Pat. No. 3,712,089, for a further description of the structure and operation of the releasable connections 114, 122 and 130 of the washer 20 beyond that required for an understanding of the present invention.

For the purpose of permitting rotation of the cylinder 42 during washing operations, and of both the casing 28 and cylinder 42 during loading and unloading operations, the cylinder and casing are mounted for rotation with respect to the frame 22. More specifically, and having reference now to FIG. 9, the cylinder 42 includes spaced side walls 134, one of which is partially illustrated. Extending radially outwardly from each side wall 134 is a trunnion shaft 136 to which is secured a cylinder drive gear, such as the drive gear 78 illustrated in FIG. 9, disposed between the inner wall 60 and outer wall 62 of the corresponding end frame 24. Drive gear 78 includes a laterally extending hub portion 138 surrounding and keyed to the trunnion shaft 136 for a portion of its length.

Sandwiched between the cylinder wall 134 and the inner wall 60 of each end frame is one of the casing end walls 32 or 34, the wall 32 being illustrated in part in FIG. 9. A central hub member 140 is attached to the central region of the casing wall by means of fasteners 142. The hub member 140 surrounds the trunnion shaft 136 for a portion of its length, and a seal assembly 144 is provided for preventing the escape of washing fluids from the casing 28. Attached to the hub member 140 by suitable fasteners or other securing device (not shown) is a sleeve member 146 encircling a portion of the trunnion shaft 136, and also overlying an end portion of the drive gear hub portion 138. A bearing assembly 148 disposed between the trunnion shaft 136 and the sleeve member 146 permits relative rotation of the trunnion 136, and thus of the cylinder 42 and drive gear 78, relative to the casing 28. A bearing seal assembly 149 is clamped between the hub member 140 and the sleeve 146.

A central support member 150 is attached to the inner wall 60 of the end frame member by means of fasteners 152. Support member 150 includes an annular sleeve portion 154 encircling the sleeve member 146 attached to the casing 28. A bearing assembly 156 interposed between the sleeve portion 154 and the sleeve member 146 permits rotation of the casing 28 relative to the frame 22.

Although the rotational mounting structure for the right hand end of the washer 20 is not illustrated in detail in the drawings, this structure may in general be

similar to the structure illustrated in FIG. 9 and described above.

POSITIONING ASSEMBLY

5 An important feature of the present invention resides in the provision of the positioning assembly 50 for reliably and accurately positioning the cylinder 42 with respect to the frame 22. At the conclusion of a washing operation, it is necessary precisely to align the cylinder 10 42 with respect to the casing 28 which, at this time, is interlocked with the frame 22, in order that the door 48 of the cylinder is precisely aligned with the door opening 36 of the casing. Moreover, and as will appear in 15 greater detail hereinafter, precise positioning is desirable in order to permit operation of the coupling assembly 52 of the washer 20. In addition, prior to commencing a washing operation it is necessary once again precisely to position the cylinder 42 and the casing 28 interlocked with the cylinder 42 so that the casing door 20 opening 36 is located in the proper position for closing of the casing door 38. Here again, precise positioning is also required for operation of the coupling assembly 52 in order to uncouple the casing 28 from the cylinder 42 and to couple the casing 28 with the frame 22.

25 In general, the positioning assembly 50 of the present invention includes both an indicator generally designated as 158 and illustrated in FIG. 3 as well as a sensor arrangement generally designated as 160 and illustrated in FIGS. 10 and 11 for approximately positioning the cylinder 42 with respect to the frame 22. In addition, the positioning assembly 50 also includes a precise positioning structure generally designated as 162 for moving the cylinder 42 to a precise angular position after it has been moved to an approximate position 30 with the aid of the indicator 158 and/or the sensor 160.

More specifically, and having reference first to the indicator 158, at the right hand end of the washer 20 as illustrated in FIG. 3 there is provided an indicator plate 164 overlying the outer wall 62 of the right end frame 26. Plate 164 is constrained to rotate with the cylinder 42, as by the use of a fastener 166 connecting the plate 164 with the cylinder trunnion shaft 136 disposed at the right hand end of the machine. Mounted upon the outer wall 62 of the right end frame 26 is a co-operating annular plate 168 including spaced indicia 170. Indicator plate 164 carries a cooperating indicia 172, and because the plates 164 and 168 are clearly visible to an operator of the machine 20, the operator is able to position the cylinder 42 within the desired approximate range by operating the motors 74 until the indicia 172 is within the range provided by the indicia 170.

55 As will appear hereinafter, in the operation of the electrical control circuit 56 of the washer 20, it is desirable to provide an electrical indication in response to the location of the cylinder 42 in the desired approximate range. With reference now to FIGS. 10 and 11, the sensor assembly 160 includes a cam member 174 fixed adjacent the periphery of the drive gear 78 by means of fasteners 176. Relative to the gear 78, the cam member 174 has an angular length corresponding to the desired approximate position of the cylinder 42. A switch 178 is mounted upon a bracket 180 attached by fasteners 182 to a portion of the left end frame 24, and a switch operating shaft assembly 184 extends between the switch 178 and the cam member 174. A cam

follower 186 is engaged by the cam member 174 when the cylinder 42 is in the desired approximate position in order to operate the switch 178 by reciprocal movement of the shaft assembly 184.

In order to withdraw the cam follower 186 from the region of the cam member 174 during operation of the washer when it is not desired to position the cylinder 42, there is provided a pneumatic cylinder 188 supported upon the bracket 180. When cylinder 188 is pressurized, an operating pin 190 is moved from its illustrated retracted position to an extended position wherein it engages and moves a lever 192 pivotally mounted to the bracket 180. Movement of lever 192 results in engagement of the lever with a member 194 coupled to the operating shaft assembly 184 to the end that the shaft assembly is retracted and the follower 186 is moved clear of the cam member 174.

After the cylinder 42 has been located in the desired approximate position through operation of the indicator 158 and/or the sensor assembly 160, the precise positioning structure 162 functions precisely to position the cylinder 42 in the desired position. More specifically, and having reference now to FIGS. 8 and 9, the precise positioning structure 162 is located within a generally rectangular coupling housing 196 supported upon the outer wall 62 of the left end frame 24. Mounted on opposite side walls of the coupling housing 196 by fasteners 198 are a pair of pneumatic positioning cylinders 200 and 202. Each cylinder is of the double acting type and includes a piston assembly 204 (FIG. 9) slidably mounted within the cylinder and an operating portion 206 extending into the coupling housing 196 from the side wall thereof. Each cylinder 200 and 202 includes a first air inlet 208 for extending the operating portions 206 toward one another within the housing 196 upon pressurization of the inlets 208, and a second inlet 210 for retracting the operating portions 206 upon pressurization of the inlets 210.

A positioning block 212 (FIG. 8) is securely attached to drive gear 78 by means of fasteners 214. Block 212 is located on the gear 78 so that it lies between the positioning cylinders 200 and 202 when the cylinder 42 has been approximately positioned through the use of the indicator 158 and/or the sensor assembly 160. The block 212 extends from the interior of the left end frame 24 into the coupling housing 196. Thus, when the cylinder has been approximately positioned within the desired range, and when the air inlets 208 of the cylinders 200 and 202 are pressurized, the operating portions 206 move toward one another and capture the block 212. Each operating portion 206 includes an adjustable nose element 216, and the nose elements are adjusted so that when the operating portions 206 are each fully extended, the positioning block is precisely located in the desired position so that the cylinder 42 is positioned precisely.

In connection with the operation of the electrical control circuit 56, it is desirable to provide an electrical indication of the positions of the operating portions 206 of the positioning cylinders 200 and 202. With reference now to FIGS. 8, 12 and 13, it can be seen that each operating portion includes a collar 218 supporting a downwardly extending switch operating member 220. Mounted along the bottom wall of the coupling housing 196 are a series of four electrical switches 222, 224, 226 and 228 engageable by the switch operating members 220. A guide rail 230 located opposite the

switches 222, 224, 226 and 228 prevents the switch operating members 220 from rotating away from the switches. When each of the operating portions 206 is fully retracted away from the positioning block 212, the switches 222 and 224 are operated to provide an indication that the drive gear 78 is free to rotate without interference from the positioning cylinders. Alternatively, when both of the operating portions 206 are fully extended, the switches 226 and 228 are both operated to provide an indication that the cylinder has been precisely positioned in the desired angular position.

COUPLING ASSEMBLY

The coupling assembly 52 is provided in accordance with another important feature of the present invention in order alternatively to interlock the casing 28 with the cylinder 42 or with the frame 22. The coupling assembly 52 is reliable in operation and rugged in construction in order to be capable of firmly and positively controlling the rotation of the relatively massive washer casing 28.

More specifically, and with reference to FIGS. 8, 9 and 14, the coupling assembly 52 in general includes a first coupling structure generally designated by the reference numeral 240 for selectively interlocking the casing 28 with the frame 22 together with a second coupling structure generally designated by the reference numeral 242 for selectively interlocking the casing with the cylinder 42. In addition, there is provided an actuator generally designated by the reference numeral 244 for operating the second coupling structure 242, and in accordance with the invention there is provided an arrangement for operating the first coupling structure in response to operation of the second coupling structure in such a manner that the casing 28 is never simultaneously uncoupled from both the frame 22 and the cylinder 42.

Proceeding now to a description of the first coupling structure 240, a coupling collar 246 (FIG. 9) is attached to the outermost end of the sleeve member 146, and thus is fixed to rotate together with the casing 28. Collar 246 includes a pair of diametrically outwardly extending coupling arms 248, each of which includes a recess or slot 250 extending radially inwardly from the ends thereof. Rotatably mounted eccentric coupling members 252 are mounted upon pins or shafts 254 extending between the side walls of slots 250.

A pair of coupling brackets 256 are secured to the inner wall 60 of the left end frame 24 by fasteners 258 at diametrically opposed positions relative to the cylinder trunnion shaft 136. Each bracket 256 includes a slot 260, and as can be seen in FIGS. 9 and 14, when the casing is in its operating position as shown in FIG. 4 of the drawings, the coupling brackets 256 are aligned with the arms 248 of the coupling collar 246. In this position the slots 260 of the brackets 256 interface with the slots 250 of the arms 248.

The coupling members 252 in the illustrated arrangement comprise latching pinions having peripheral gear teeth 262 and additionally having a flat 264. In the position illustrated in FIG. 9, the pinions are rotated to an angular position wherein the flats 264 are not directed radially outwardly toward the coupling brackets 256. As a result, and as best seen in FIG. 14, the peripheral portions of the coupling members 252 extend into interlocking engagement with the slots 260 of the coupling brackets 256. Consequently, the collar 246 is held

in a fixed position and the casing 28 is held against rotation. In order to prevent inadvertent rotation of the coupling members 252 from this interlocked condition, each coupling bracket 256 is provided with a spring biased ball detent 266 (FIG. 14) engageable with a cooperating recess in the corresponding coupling member 252.

With reference now to the second coupling structure 242, the drive gear 78 is provided with a pair of annular bosses 268 in diametrically opposed positions. When the casing 28 is disposed in its operating position, and when the cylinder 42 has been positioned in the coupling position by means of the positioning assembly 50, the bosses 268 are aligned with the innermost portions of the slots 250 in the arms 248 of the coupling collar 246.

Slidably disposed in each of the bosses 268 is a coupling member 270 in the form of an elongated pin or shaft. In the position illustrated in FIG. 9, the shafts 270 are disposed in a retracted position and the cylinder 42 is not coupled to the casing 28 but rather is free to rotate independently.

Each of the coupling members 270 is adapted to be moved to an extended position wherein the coupling members 270 enter the slots 250 in the arms 248 of the coupling collar 246. As appears both in FIG. 9 and FIG. 14, the leading ends 272 of the coupling members 270 are somewhat rectangular so that they are complementary in shape with the slots 250. When the coupling members are in the extended position, the collar 246 is interlocked with the drive gear 78 and as a result the casing 28 is interlocked with the cylinder 42.

In accordance with a feature of the invention, movement of the coupling members 270 from the uncoupled position to the coupled position results in movement of the coupling members 252 from the coupled position to the uncoupled position. More specifically, the ends 272 of the coupling members 270 are provided with gear teeth 274 which cooperate with the gear teeth 262 of the coupling pinions 252. As a result, when the coupling members 270 move into the slots 250, the teeth 274 engage the teeth 262 of the pinions 252 and cause them to rotate through substantially ninety degrees of rotation. Consequently, the flats 264 of each member 252 are positioned generally parallel with the outer edges of the slots 260 of the coupling brackets 256. In this position the coupling members 252 do not enter the slots 260 and the collar 246 is no longer interlocked with the coupling brackets 256. Thus, the casing 28 is uncoupled from the frame 22 shortly after it is coupled with the cylinder 42.

Importantly, at no time during the operation of the coupling assembly 52 is the casing 28 uncoupled from both the frame 22 and the cylinder 42. More specifically, it is necessary for the coupling members 270 to enter the slots 250 prior to the time that the coupling members 252 disengage the slots 260. As a result, the casing 28 cannot inadvertently be rotated independently of the cylinder 42 to a position wherein the coupling assembly 52 would not be operable due to misalignment of the bosses 268 and the slots 250.

In order to permit automated remote operation of the coupling assembly 52, the actuator 244 is provided. This actuator 244 includes a pneumatic cylinder 276 mounted in a central location on the hub portion 138 of the drive gear 78 by means of fasteners 278. The cylinder includes an inner end wall 280 having an air inlet

282 and an outer end wall 284 having an air inlet 286. A piston assembly 288 reciprocates within the cylinder 276 in response to pressurization of the air inlets 282 and 286 and is coupled to an operating shaft 290 extending outwardly of the cylinder 276. A coupling drive yoke 292 is carried by shaft 290 and includes diametrically opposed arm portions 294 fastened to the outermost ends of the coupling members 270.

When the air inlet 282 is pressurized, the coupling assembly 52 assumes the position illustrated in FIG. 9 wherein the coupling members 270 are in their retracted position so that the cylinder 42 is free to rotate independently of the casing 28 and so that the casing 28 is interlocked with the frame 22. When the air inlet 286 is pressurized, the piston assembly 288 moves to its alternate position and as a result the coupling members 270 are moved to their extended position to interlock the cylinder 42 with the casing 28 and to release the casing 28 from the frame 22.

In connection with the operation of the electrical control circuit 56, it is desirable to provide an electrical indication of the condition of the coupling assembly 52. As best illustrated in FIGS. 8 and 9, a generally circular position indicating plate 296 is attached to the coupling drive yoke 292 by means of fasteners 298. A pair of electrical switches 300 and 302 are mounted on a pair of support brackets 304 and 306 carried on a support rod 308 mounted within the coupling housing 196. The brackets 304 and 306 are adjustable to positions wherein the switch 300 is operated when the casing 28 is uncoupled from the cylinder 42 and is coupled to the frame 22 and so that the switch 302 is operated in the alternate position wherein the casing 28 is coupled to the cylinder 42 and uncoupled from the frame 22.

Permanent air connections cannot readily be made from the frame 22 to the coupling assembly actuator air inlets 282 and 286 because the actuator 244 is mounted in a fixed position relative to the rotatable cylinder 42. For this reason there is provided a releasable air connection generally designated by the reference numeral 310 and best illustrated in FIGS. 8 and 9. One of the annular bosses 268 of the drive gear 78 includes a pair of air inlet passages 312 and 314 (FIG. 9) leading to a pair of pneumatic conduits 316 and 318 (FIG. 8) permanently connected to the actuator air inlet passages 282 and 286. When the cylinder 42 has been precisely positioned by the positioning assembly 50, the air inlet passages 312 and 314 are aligned with a pair of air supply passages 320 and 322 in an air supply block 324 mounted for reciprocal movement within the coupling housing 196. A pneumatic cylinder 326 including a pair of air inlets 328 and 330 controls the position of the air supply block 324 by virtue of a piston assembly 332 and an operating shaft 334. The air supply passages 320 and 322 are connected to air supply lines adapted to be selectively pressurized for operating the actuator 244 of the coupling assembly 52. When the air inlet 328 of the cylinder 326 is pressurized, the air supply block 324 is in the position illustrated in FIG. 9 wherein the air supply passages 320 and 322 are connected respectively with the air inlet passages 312 and 314. Alternatively, when the air inlet 330 of the cylinder 326 is energized, the air supply block 324 moves to its alternate position wherein no connections are made between the air supply passages 320 and 322 and the air inlet passages 312 and 314.

In order to provide an electrical indication of the condition of the releasable air connection 310, a switch 336 is mounted to the coupling housing 196 adjacent the air supply block 324. A switch operating lever 338 is coupled between the air supply block 324 and the switch 336 to the end that the switch 336 is operated to alternate conditions depending upon the position of the air supply block 324.

CONTROLS AND OPERATION

Further important aspects of the present invention will appear from consideration of the pneumatic control circuit 54 and the electrical control circuit 56 illustrated in FIGS. 15 and 16 of the drawings. The pneumatic control circuit 54 serves to control the application of pressurized air from a suitable pressure source 340 to the various pressure operated actuators and cylinders described above and illustrated in FIGS. 1-14. The electrical circuit 56 controls the energization of various components from a suitable power supply 342. The circuits 54 and 56 are highly integrated with one another in operation, and these circuits are described together in the following detailed description of the operation of the washer 20.

The pneumatic and electrical control circuits 54 and 56 are depicted in FIGS. 15 and 16 in the condition assumed just prior to the beginning of a washing cycle of the washer 20. Referring first to the electrical control circuit 56, in general this circuit includes a manually operated main control switch 344 operable alternatively to a "run" or to a "load — unload" position. Circuit 56 also includes a door controlling circuit generally designated as 346 for controlling the operation of the door operating structure 40, a positioning circuit generally designated as 348 operable in conjunction with the positioning assembly 50, a coupling circuit generally designated as 350 for controlling portions of the positioning assembly 50 and for controlling the coupling assembly 52, and a motor control circuit generally designated as 352 for controlling the operation of the washer drive motors 74.

In the illustrated condition of circuit 56, the main switch 344 is in the "run" position, and as a result the positioning and coupling circuits 348 and 350 are inactive, the door controlling circuit 346 operates to hold the casing door 38 in the closed position, and the motor control circuit 352 is conditioned for the initiation of a washing operation.

More specifically, the main switch 344 (FIGS. 1 and 3) is disposed upon the front panel of a control console 354 located on the right end frame 26 of the washer 20 convenient to the operator of the machine. Switch 344 includes a plurality of contactors all designated by the reference numeral 344 and ganged together for simultaneous operation as indicated by a broken line in FIG. 16. In the illustrated "run" condition, main switch contacts 344A, 344D, 344G, 344J, 344M, 344O, 344P and 344Q are closed in order to establish a circuit including the motor control circuit 352 for carrying out a washing operation. Conversely, contacts 344B, 344C, 344E, 344F, 344H, 344I, 344K, 344L 344N are maintained in the open circuit condition in order to disable the positioning and coupling circuits 348 while the washer 20 is running. A power transformer 356 supplies operating potential to the circuit 56 from the power supply 342. Fuses 358 are provided for overload protection.

In order to prevent operation of the drive motors 74 during possibly unsafe conditions, several interlock arrangements are provided. The coupling switch 300 includes a set of contacts 300A in series with main switch contacts 344A to open the circuit to the motor control circuit 352 unless the coupling switch 300 is operated by full outward movement of the indicating plate 269 (FIG. 9) to the position indicating that the casing 28 is coupled to the frame 22 and that the cylinder 42 is free for independent rotation. Also in series with main switch contacts 344A are contacts 91A of the switch 91 associated with the door operating structure 40. Contacts 91A disable the motor control circuit 352 unless the door 38 is in its closed position against the casing 28 (FIGS. 4-7).

Connected in series with main switch contacts 344D is a circuit breaking device schematically illustrated as a set of switch contacts 360. These contacts comprise a circuit path extending through the circuit established by the elelctrical releasable connection 130. Since the releasable connections 104, 114, 122 and 130 all open and close simultaneously, the contacts 360 serve to prevent operation of the motor control circuit 352 until the water, water level, steam and electrical connections have been made to the casing 28.

As can be seen in FIG. 16, switches 222 and 224 are also connected between the main switch contacts 344D and the motor control circuit 352. These switches are closed only when the operating portions 206 of the positioning cylinders 200 and 202 (FIG. 8) are fully retracted to permit unobstructed rotation of the cylinder 42.

When contacts 300A, 91A, 360, 222 and 224 are all closed, a washing cycle wherein the cylinder 42 is rotated may safely be carried out. At this time, a circuit including closed main switch contacts 344Q energizes a main air supply solenoid 362 in order to condition the pneumatic control circuit 54 for a washing operation. With reference now to FIG. 15, it can be seen that the main air supply solenoid 362 controls the position of a main air supply four-way valve 364 connected to the pressure source 340. In the illustrated energized condition of solenoid 362, valve 364 is operated and supplies pressurized air to the cylinder 188 (FIG. 11) to maintain the cam follower 186 in its retracted position, and to each of the actuators 106, 120, 128 and 132 of the releasable connections 100, 114, 122 and 130. At this point it should be noted that a manually operated bypass switch 366 (FIGS. 1 and 16) is provided for permitting energization of solenoid 362 for a brief period of time prior to the closure of the electrical connection 130 and of the contacts 360.

During the time that the washer 20 is conditioned for a washing operation, the door 38 is positively held closed. Main air supply valve 364 in its operated position provides a path for exhausting the door raising inlet of the cylinder 88 associated with the door operating structure 40 to permit the door 38 to remain closed. In FIG. 16 it can be seen that a door lowering solenoid 367 is energized when the main switch 344 is in the "run" position, when switch 92 is closed due to the door carriage 86 being in the forward position (FIGS. 4-7), and when contacts 300A are closed. This solenoid 367 operates a door lowering three-way valve 368 (FIG. 15) connected between the pressure source 340 and the door lowering inlet of the cylinder 88. In the illustrated operating position, valve 368 pressurizes cyl-

inder 88 tightly to clamp the door 38 in its down position. Similarly, a door forward solenoid 369 is energized to move a door forward valve 370 to its operated position wherein cylinder 90 is pressurized and carriage 86 is held in its forward position.

In order to maintain the releasable connection 310 of the coupling assembly 52 (FIG. 9) in retracted position free of the cylinder 42, a four-way coupling air supply control valve 372 is provided. In the illustrated nonoperated position, valve 372 pressurizes the inlet 330 and vents the inlet 328 of the air supply cylinder 326. Similarly, positioning cylinders 200 and 202 are maintained in the retracted position by means of a four-way positioning control valve 374. In the illustrated nonoperated position of valve 374, the valve pressurizes the inlets 210 and vents the inlets 208 of the positioning cylinders 200 and 202.

With reference once more to FIG. 16, in order to begin a washing cycle after the washer 20 is conditioned for "run" operation, a start switch 376 is operated momentarily. Switch 376 may be a manually operated switch or alternatively may comprise a switch operated automatically by a program controlling device such as the device disclosed in my U.S. Pat. No. 3,602,096, issued on August 31, 1971. When switch 376 is operated, contacts 376A are opened and contacts 376B are closed to complete a path including main switch contacts 344J for the energization of the winding of a brake release relay 378. A normally open set of relay contacts 378A close to complete a holding circuit including main switch contacts 344J for maintaining winding 378 energized after momentary operation of the start switch 376.

Conversely, at the end of the washing cycle or at any other time when it is desired to halt the washer 20, a stop switch 380 is momentarily operated either manually or automatically. When switch 380 is operated, the holding circuit for relay winding 378 is interrupted and the relay 378 is deenergized until such time as the start switch 376 is again operated.

Energization of relay 378 also results in closing of a normally open set of contacts 378B, whereupon a brake release solenoid 382 is energized by a circuit including closed relay contacts 378A and main switch contacts 344G. As illustrated in FIG. 15, motors 74 are provided with spring loaded brakes 384 normally holding the motors 74 and thus the cylinder 42 stationary. When energized, solenoid 382 operates a brake release valve 386. In its illustrated nonoperated position, valve 386 vents a pair of brake release pneumatic cylinders 388. When moved to its alternate operated position by energization of solenoid 382, valve 386 pressurizes cylinders 388 and the brakes 384 are withdrawn to permit operation of the motors 74.

When the start switch 376 returns to its initial illustrated position, a circuit is established through contacts 376A, 380A and 378A for the energization of the motor control circuit 352. The circuit 352 includes a pair of motor control relay windings 390 and 392 controlling contacts (not shown) for operating the motors 74 in opposite directions. Windings 390 and 392 are connected in series with main switch contacts 344M and 344O respectively. In order periodically to reverse the direction of rotation of cylinder 42 during the washing operation, a pair of switches 394 and 396 are alternately closed by a cam 398 rotated by a timing motor 400 connected in series with main switch contacts

344P. The rotation of the cylinder 42 alternately in opposite directions continues until the stop switch 380 is momentarily operated to deenergize relay 378, whereupon the motor control circuit 352 is deenergized and the brakes 384 are reapplied.

At the conclusion of a washing operation, the operator may condition the machine 20 for unloading the washed load and for receiving a new laundry load by operating the main switch 344 from the illustrated 10 "run" position to the alternate "load — unload" position. As a result, switch contacts 344A and 344D are opened to disconnect the circuit for operation of the motor control circuit 352 and to initiate an automatic operation during which the casing door 38 is opened 15 and the casing 28 is otherwise freed for rotation.

More specifically, when contacts 344A and 344B are opened, the circuit for energization of the main air supply solenoid 362 is interrupted and the main air supply valve 364 moves from its illustrated operated position 20 to its alternate nonoperated position. In this position the cylinder 188 is vented to extend the cam follower 186, and the actuators 106, 120, 128 and 132 are vented so that the releasable connections 104, 114, 122 and 130 are opened. When the releasable electrical connection 130 is fully opened, switch 133 (FIGS. 15 and 16) is operated to prepare a circuit for energization of the positioning circuit 348.

Opening of main switch contacts 344A and 344D also breaks the circuit for energization of the door lowering solenoid 367 and as a result the door lowering valve 368 moves to its nonoperated position to vent the door lowering inlet of the cylinder 88. Similarly, the door forward solenoid 369 is deenergized so that the door forward valve 370 moves to its nonoperated position to vent the door forward inlet of the cylinder 90. 35

When the main air supply valve 364 moves to its nonoperated position, the door raising inlet of the cylinder 88 is pressurized and the door 38 moves upwardly to its raised position. At this time the switch 91 (FIGS. 4-7 and 16) is operated to its alternate condition and switch contacts 91B close to complete a circuit including main switch contacts 344B and 344C for energizing a door retracting solenoid 402. As a result a door retracting valve 404 is moved to its operated position and the door retracting inlet of cylinder 90 is pressurized to move the carriage 86 and the door 38 toward the rear of the washer 20.

At the conclusion of the rearward movement of the carriage 86, the electrical circuit 56 is placed in condition for operation of the positioning and coupling circuits 350. More specifically, when the door is fully withdrawn, contacts 93A of the switch 93 (FIGS. 4-7 and 16) are closed to complete a circuit including main switch contacts 344F and 344H as well as switch 133 permitting the operation of the positioning circuit 348.

It will be appreciated that when the cylinder 42 is halted at a random position following a washing operation, positioning of the cylinder 42 relative to the stationary casing 28 is necessary prior to operation of the coupling circuit 350. In order to operate the positioning assembly 50 of the washer, the positioning circuit is provided with a pair of push-pull manually operated, three position switches 406 and 408 including normally open switch contacts 406A, 406B, 408A and 408B. Switches 406 and 408 are conveniently mounted on the 60 65

console 354 (FIG. 1). For safety purposes each switch 406 and 408 is spring biased to its illustrated position wherein all switch contacts are open and wherein the positioning circuit 348 and coupling circuit 350 do not operate. The switches may be manipulated by either pushing or pulling to close either one or the other of the two contacts controlled by each switch. If the operator releases either switch 406 or 408 at any time, the switch returns due to the spring bias to its intermediate nonoperated position. Consequently, the operator cannot leave either switch in an operated condition when he is not positioned at the console 354.

Each switch 406 and 408 is provided with an indicator lamp 410 and 412 respectively. Preferably the lamps are mounted in the switch operating buttons (FIG. 1) to indicate to the operator that the circuitry controlled by the particular switch is prepared for use. Thus, when switch 93 is operated and the positioning circuit 348 is conditioned for operation, the indicator 410 is energized.

To begin the positioning operation, switch 406 is operated to close contacts 406B. As a result a circuit is completed through main switch contacts 344I for the energization of the "run" relay 378 and contacts 378B close to energize the brake release solenoid 382. Valve 386 (FIG. 15) is operated and the brakes 384 are released to free the motor 74 for operation. Since the main switch 344 is not in the "run" position, relay contacts 378A have no function during the positioning operation. Closing of switch contacts 406B also extends a circuit to the contacts 408A and 408B of the switch 408 and to the indicator 412.

At this time the operator can either pull or push switch 408 alternatively to energize motor relay 392 through main switch contacts 344N or to energize motor relay 390 through main switch contacts 344L. Thus by manipulating switch 408, the operator can "inch" or intermittently move the casing in either direction until the casing is located in the proper desired approximate range displayed by indicator 158 (FIG. 3). As soon as the cylinder 42 reaches the desired approximate position, cam operated switch 178 (FIGS. 10 and 11) is operated by cam 174 and cam follower 186, and switch contacts 178A open while switch contacts 178B close. Opening of contacts 178A breaks the circuit to the switch 408 established by switch contacts 406B so that the cylinder 42 halts regardless of the position of switch 408. Opening of contacts 178A also deenergizes relay winding 378 so that contacts 378B open and the brake release solenoid 382 and the brake release valve 386 function to reapply the brakes 384 to the motors 74. Closing of contacts 178B extends a circuit through previously closed switch contacts 93B to the coupling circuit 350. An indicator 414 disposed on the console 354 is energized at this time to indicate to the operator that the coupling circuit 350 may now be used.

The coupling circuit 350 operates automatically to carry out a precise positioning operation through control of the precise positioning structure 162 followed by a coupling operation through control of the coupling assembly 52. In the illustrated condition, the cylinder 42 is uncoupled from the casing 28 and the casing 28 is coupled to the frame 22. As a result, a pair of switch contacts 300B of the coupling switch 300 are closed to energize an indicator 416 disposed on console 354. This indicator apprises the operator of the machine

that the casing 28 is in the "run" condition,—i.e., coupled to the frame 22 and not to the cylinder 42.

In order to initiate operation of the coupling circuit 350, the operator closes a switch 418 also mounted on the console 354. Closing of switch 418 completes a circuit for energizing a relay winding 420 through a circuit including contacts 302A of coupling switch 302 and including normally closed relay contacts 422A and 422B of a relay winding 422 which is not energized at this time. Relay contacts 420A close to establish a holding circuit for relay 420 so that the relay 420 remains energized after the switch 418 is released. Normally open sets of relay contacts 420B and 420C close to energize a positioning solenoid 424 controlling the positioning control valve 374 (FIG. 15).

When valve 374 moves to its operated position the inlets 208 of the positioning cylinder 200 and 202 are pressurized, while the inlets 210 are vented. Operating portions 206 move together and capture the positioning block 212 therebetween. A pressure sensing device 426 controlling a pressure responsive switch 428 (FIGS. 15 and 16) is in communication with the inlets 208, and when the block 212 is engaged by one of the operating portions 206, a pressure increase is sensed by device 426 and switch 428 is operated. As can be seen in FIG. 16, switch 428 completes a circuit for energization of a brake vent solenoid 430, and solenoid 430 moves a brake vent valve 431 to its operated position.

The inlet brake vent valve 431 is communicated with the positioning valve 374 and thus is pressurized in common with air inlets 208 of the positioning cylinders 200 and 202. When valve 431 is operated, pressure is applied through the normal vent passage of the brake release valve 386 to pressurize the cylinders 388 and release the brakes 384. As the brakes are released with increasing pressure, the operating portions 206 of the positioning cylinders 200 and 202 are permitted to move the block 212 and thus the cylinder 42 to the exact position required for operation of the coupling assembly 52.

When operating portions 206 of the positioning cylinders 200 and 202 are fully extended, the positioning switches 226 and 228 are operated by switch operating member 220 (FIGS. 8, 12 and 13) from the normally opened condition to the closed condition. As a result a circuit path is completed for energization of a time delay relay winding 432 having a set of normally open relay contacts 432A. During a brief time delay period prior to closing of contacts 432A, the load contained in the cylinder 42 is permitted to settle to a static position so that the cylinder 42 becomes stable in its precisely determined coupling position.

Closing of contacts 432A completes a circuit for energization of a coupling air supply solenoid 434 controlling the coupling air supply control valve 372. Valve 372 is moved to its operated position to vent the air inlet 330 of the air supply cylinder 326 and to pressurize the inlet 328. Consequently, the cylinder 326 operates to move the air supply block 324 into engagement with the air inlets 312 and 314 leading to the coupling cylinder 276. When this connection is completed, switch 336 is operated by lever 338 from its normal open circuit condition to a closed circuit condition in order to extend a circuit connection to a pair of coupling solenoids 436 and 438 in series respectively with normally open relay contacts 420D and 422C of the re-

lays 420 and 422. Since at this time the relay 422 is de-energized while the relay 420 is energized, only the solenoid 436 is energized.

As shown in FIG. 15, solenoids 436 and 438 respectively control a pair of coupling control valves 440 and 442. When valve 440 moves to its operated position due to energization of solenoid 436, the inlet 282 of the coupling cylinder 276 is pressurized through passages 322, 314 and 316. Consequently, the cylinder 42 is coupled to the casing 28 by coupling members 270, and the coupling members 252 are moved to free the casing 28 from the frame 22. In response to this movement, the position indicating plate 296 (FIG. 9) first releases coupling switch 300 and then operates coupling switch 302.

Release of switch 300 opens contacts 300A connected in series with main switch contact 344A, to prevent "run" operation of the washer 20 while the casing 28 is uncoupled from the frame 22. Contacts 300B open to deenergize the indicator lamp 414. Contacts 300C close, but have no effect at this time because normally closed relay contacts 420E and 420F are open during energization of relay 420.

Upon completion of movement of the coupling cylinder 276, switch 302 is operated to open contacts 302A and to close contacts 302B. Opening of contacts 302A breaks the circuit for energization of relay 320 so that its contacts return to the normal condition and solenoids 430, 424, 434 and 436 are deenergized. When solenoid 430 is deenergized, brake vent valve 431 returns to its illustrated position (FIG. 15) to vent brake cylinders 388 through valve 386, and the brakes 384 are reapplied to motor 74. Deenergization of solenoid 424 causes the positioning control valve 374 to return to its illustrated position and the operating portions 206 of positioning cylinders 200 and 202 are retracted. Deenergization of solenoid 434 results in retracting of the air supply block 324 by operation of coupling air supply cylinder 326. Deenergization of solenoid 436 results in depressurization of the passages leading to the coupling cylinder 276. The coupling assembly 52 due either to friction or to suitable detent means if desired remains in its existing condition with casing 28 freed from frame 22 and coupled to cylinder 42. Closure of contacts 302B completes a circuit for energization of an indicator lamp 444 located on the console 354 to inform the operator that unloading and loading operations may now be carried out.

Unloading of the washer is accomplished by simultaneously rotating the coupled cylinder 42 and casing 28 through the use of the positioning circuit 348. More specifically, in order to rotate the casing 42 away from its coupling position wherein cam operated switch 178 is in its operated position, the manual switch 406 is actuated to close contacts 406A to provide a circuit connection through main switch contacts 344I and 344K to the switch 408. Since contacts 406A bypass the contacts of the cam operated switch 178 and since the contacts 406B are opened when contacts 406A are closed, the coupling circuit 350 cannot be energized during loading and unloading regardless of the position of the cylinder 42.

Because closing of contacts 406A energizes relay 378 to release the brake 384, the coupled cylinder and casing can be rotated through operation of switch 408 from the position shown in FIG. 5 to the position shown in FIG. 6 wherein the cylinder door 48 may be opened.

The cylinder 42 and casing 28 are then rotated switch 408 to the unloading position of FIG. 7 and then to the loading position of FIG. 5 wherein the washed laundry load is discharged and a new load is deposited into the machine. The cylinder and casing are then moved once again to the FIG. 6 position and the cylinder door 48 is closed.

Prior to beginning a new washing cycle it is necessary to uncouple the casing 28 from the cylinder 42 and to couple the casing 28 to the frame 22. Switch 406 is operated to its alternate position opening contacts 406A and closing contacts 406B to place cam operated switch 178 in the circuit. When the approximate desired position is reached through use of the switch 408, the positioning circuit 350 is again activated and indicators 414 and 444 are again energized.

In order to operate the coupling circuit 350 to uncouple the casing 28 from the cylinder 42 and to couple it to frame 22, a manual switch 446 located on console 20 354 is closed to complete a circuit through closed contacts 300C for energization of the relay 422. Contacts 422A and 422B open to isolate the relay 420, while contacts 422C close to prepare a circuit for energization of coupling solenoid 438. Additional normally open contacts 422D, 422E and 422F close to establish a holding circuit for the relay 422 and to energize the positioning solenoid 424. In the manner described above, the positioning cylinders 200 and 202 are pressurized, the switch 428 and solenoid 430 are operated, the brakes 384 are released, and the coupled cylinder 42 and casing 28 are precisely positioned in the coupling position.

When the positioning switches 226 and 228 close, time delay relay 432 is energized, and thereafter the air supply solenoid is energized to complete the air connection to the coupling cylinder 276. When switch 336 is operated, solenoid 438 is energized and coupling valve 442 operates to pressurize coupling cylinder 276 so that coupling members 252 interconnect the casing 28 and the frame 22, while coupling members 270 retract to free the cylinder 42 for rotation independent of the casing 28. At the conclusion of the coupling operation, when switches 300 and 302 return to their illustrated positions, relay 422 and solenoids 424, 430, 434 and 438 are deenergized to reapply the brakes 384, withdraw the operating portions 206 of the positioning cylinders 200 and 202, depressurize the coupling cylinder 276, and to retract the air supply block 324. In order to begin another washing cycle, the main switch 344 may be returned to the illustrated "run" position, whereupon both the pneumatic control circuit 54 and the electrical control circuit 56 are returned to their initial, illustrated condition described above.

Although the present invention has been described in connection with the details of the illustrated embodiment, it should be understood that such details are not intended to limit the invention which is defined in the following claims.

What is claimed and desired to be secured by Letters Patent of the United States is:

1. A laundry machine comprising a frame, an inner cylinder and an outer casing supported for rotation on said frame, a first coupling means mounted on said casing and movable between a first position engaging said frame to hold said casing stationary and a second position wherein said first coupling means is spaced from said frame to permit rotation of said casing, a second

coupling means mounted on said cylinder and movable between a first position wherein said second coupling means is spaced from said casing to permit rotation of said cylinder independent of said casing and a second position wherein said second coupling means engages said casing for simultaneous rotation of said casing and cylinder, and means coupled between said first and second coupling means constraining said first and second coupling means for simultaneous movement between their respective first and second positions.

2. The laundry machine of claim 1 wherein said second coupling means engages said casing before said first coupling means disengages said frame during said simultaneous movement from said first positions to said second positions.

3. The laundry machine of claim 1, said first coupling means comprising an eccentric latch member mounted for rotational movement, means on said frame defining a slot for receiving a radially extensive segment of said latch member upon rotation of said latch member to said first position, said second coupling means comprising an axially movable pin, and means on said casing defining a recess for receiving said pin upon movement of said pin to said second position.

4. The laundry machine of claim 3, said latch member being disposed at least in part within said recess in the path of movement of said pin.

5. The laundry machine of claim 4, said latch member including pinion gear teeth and said pin including rack gear teeth engaging said pinion gear teeth upon movement of said pin into said recess.

6. The laundry machine of claim 5, detent means on said casing engageable with said latch member for holding said latch member in said first position following movement of said pin to its first position.

7. The laundry machine of claim 6 further comprising an air cylinder mounted on said casing for moving said pin between its first and second positions.

8. The laundry machine of claim 7 further comprising sensing means associated with said air cylinder for providing an indication of the positions of said first and second coupling means.

9. A laundry machine comprising an inner cylinder, an outer casing surrounding said inner cylinder, a pair of end frames supporting both said cylinder and said casing for rotation about a common axis, a drive motor coupled to said cylinder for rotating said cylinder, and a coupling assembly for controlling the rotation of said casing, said coupling assembly including a first member fixed to one end frame, a second member fixed to said casing and disposed adjacent said first member in a predetermined angular position of said casing relative to said end frame, first coupling means mounted on said second member and normally engaging said first member to fix said casing to said frame and prevent rotation of said casing, said first coupling means being movable to a position spaced from said first member to free said casing for rotation relative to said frame, a third member fixed to said cylinder and disposed adjacent said second member in a predetermined angular position of said cylinder relative to said casing, second coupling means mounted on said third member and normally spaced from said second member to permit rotation of said cylinder independent of said casing, said second coupling means being movable into engagement with said second member to interlock said casing with said cylinder for simultaneous rotation, and means for mov-

ing said first coupling means to said position spaced from said first member in response to movement of said second coupling means to said position in engagement with said second member.

5 10. The laundry machine of claim 9, said first member including a slot having an opening adjacent said second member, and said first coupling means comprising a pinion gear disposed in said slot in the normal position of said first coupling means and having a flat permitting said pinion gear to clear said slot when rotated to said spaced position.

11. The laundry machine of claim 10, said second member including a recess, said pinion gear being disposed at least in part in said recess, said second coupling means including a pin movable axially into and out of said recess, and rack gear teeth on said pin engaging said pinion gear for rotating said pinion gear in response to axial movement of said pin within said recess.

15 20. 12. The laundry machine of claim 11 further comprising actuating means on said first member for axially moving said pin.

25 13. The laundry machine of claim 12 further comprising positioning means coupled between said frame and said cylinder for positioning said cylinder in a predetermined angular position relative to said frame, and means responsive to said positioning means for disabling said actuating means unless said cylinder is in said predetermined position relative to said frame.

30 35 14. A laundry machine comprising a pair of end frames, a cylinder mounted between said frames for rotation around its central axis, a structural element fixed to said cylinder for rotation therewith and disposed adjacent one said end frame, a projection carried by said structural element, a first positioning means for locating said cylinder within a predetermined range of angular positions wherein said projection is disposed in a predetermined region, and second positioning means mounted on said one end frame and engageable with said projection in said region for locating said projection at a predetermined position in said region thereby to locate said cylinder in a predetermined angular position.

40 45 15. The laundry machine of claim 14, further comprising control means for operating said second positioning means in response to the presence of said projection in said region.

50 16. The laundry machine of claim 14, said first positioning means including a cam mounted on said structural element and a cam operated device engageable with said cam in said predetermined region.

17. The laundry machine of claim 14, said structural element comprising a cylinder drive gear.

55 18. The laundry machine of claim 14, said second positioning means comprising a pair of interfacing air cylinders including operating portions movable to extended and retracted positions, said operating portions in said extended positions being spaced apart by a distance generally equal to the thickness of said projection.

60 19. The laundry machine of claim 18 further comprising sensing means operated by said operating portions for providing an indication when said cylinder is located in said predetermined position.

65 20. A laundry machine comprising a frame including a pair of end frames, an inner cylinder and an outer casing mounted for rotation about an axis extending be-

tween said end frames, coupling means for coupling said casing alternatively to said frame and to said cylinder, positioning means for locating said cylinder in a predetermined angular position relative to said frame, actuator means for operating said coupling means, and means controlled by said positioning means for operating said actuating means only after operation of said positioning means.

21. The laundry machine of claim 20 further comprising a casing door mounted on said frame movable between a closed position in engagement with said casing and an open position spaced from said casing, and means for operating said positioning means only when said casing door is in the open position.

22. The laundry machine of claim 21, drive motor means on said frame for rotating said cylinder, first drive control means for operating said drive motor means substantially continuously during a laundry cycle, and means for operating said first drive control means only when said door is closed and said casing is coupled to said frame.

23. The laundry machine of claim 22, second drive control means for operating said drive motor means intermittently during loading and unloading operations, and means for operating said second drive control means only when said casing door is open.

24. The laundry machine of claim 23, said last recited means including a manual switch for disabling said second drive control means except during manual contact with said switch.

25. A laundry machine comprising a frame, an inner cylinder and an outer casing mounted on said frame for rotation around a common horizontal axis, drive motor means mounted on said frame and drivingly coupled to said cylinder, casing door means mounted on said frame and movable to an open position spaced from said casing and to a closed position engaged with said casing in a predetermined position of said casing to close said casing, positioning means engageable with said cylinder for moving said cylinder to a predetermined position, coupling means for coupling said casing alternatively to said frame and to said casing, con-

trol means, first switch means operable to place said control means in a run condition for operating said motor means and disabling said positioning and coupling means, means for disabling said control means in the run condition of said control means unless said casing is in said predetermined position and unless said casing is coupled to said frame, and means for holding said door means in said closed position when said control means is in said run condition.

10 26. The laundry machine of claim 25, said first switch means being operable to place said control means in a load condition for deenergizing said motor means, and means for opening said door means in response to placing of said control means in said load condition.

15 27. The laundry machine of claim 26, second switch means for operating said positioning means, and means for enabling said second switch means in response to opening of said door means.

20 28. The laundry machine of claim 27, said positioning means including circuit means including said second switch for energizing said motor means.

25 29. The laundry machine of claim 28, said second switch means comprising a manually operated switch, a switch operating member, and means for closing said switch only during manual contact of said member.

30 30. The laundry machine of claim 27, means including third switch means for operating said coupling means, and means for disabling said coupling means until after operation of said positioning means.

35 31. The laundry machine of claim 30 further comprising brake means operatively coupled to said motor means, said control means including means for releasing said brake means in the run condition of said control means, and said positioning means including means for releasing said brake means during operation of said positioning means.

40 32. The laundry machine of claim 31 further comprising releasable connections between said frame and said casing, and said control means including means for closing said releasable connections only in the run condition of said control means.
